(57) **CLAIM**

The ornamental design for a mobile communication terminal, as shown and described.

DESCRIPTION

FIG. 1 is a front perspective view of a mobile communication terminal;

FIG. 2 is a front view of the mobile communication terminal of FIG. 1;

FIG. 3 is a rear view of the mobile communication terminal of FIG. 1;

FIG. 4 is a left-side view of the mobile communication terminal of FIG. 1;

FIG. 5 is a right-side view of the mobile communication terminal of FIG. 1;

FIG. 6 is a top plan view of the mobile communication terminal of FIG. 1; and,

FIG. 7 is a bottom plan view of the mobile communication terminal of FIG. 1.

The broken lines shown in the figures that are immediately adjacent to the shaded areas and define unshaded regions represent the bounds of the claim. All other broken lines, including any features or group of features shown in broken lines that are superimposed on shaded surfaces, are directed to environment and are for illustrative purposes only. The broken lines form no part of the claimed design.

1 Claim, 7 Drawing Sheets
